UNITED STATES PATENT OFFICE

GEZA GREENBERG, OF NEW YORK, N. Y.

GARMENT SUPPORT

Application filed July 2, 1930. Serial No. 465,286.

The present invention relates particularly to men's garment supports, which will take the place of and eliminate the need for belts, suspenders, or equivalent conventional trouser supporting mediums.

While the invention is broadly applicable, it relates particularly to garment support arranged to connect trousers to shirt, to the end that the trousers will be effectively maintained in elevated position, while the shirt is retained in proper position and against wrinkling, creasing, or blousing effect. This invention is an improvement on my prior Patent No. 1,693,030, issued November 27, 1928.

It is among the more general objects of the invention to provide an inexpensive and efficient trouser support which is applicable to support the trousers from a shirt and to distribute the supporting strain throughout the material of the shirt in such manner as to avoid concentrated strains on the shirt material and in such manner as to prevent wrinkling or blousing of the shirt.

One of the more specific objects is to provide an improved means for supporting a pair of trousers from a shirt, which may be readily applied and removed from the trousers without the use of the conventional suspender buttons of the trouser waistband.

Another object is to provide a garment support of the character set forth, which may be formed during the manufacture of the garment and permanently applied to the waistband thereof.

Another object is to provide a garment support formed during the manufacture of the trousers, which will be applicable to the waistband thereof without any modification of present waistband constructions.

Another object is to provide a securing medium for trousers, which is wholly encased and protected against contact of its metal portions with the body or garments of the wearer.

Another object is to provide a garment support comprising a small self-contained and protected structure which may be readily applied to a trouser waistband and which will effectively prevent accidental displacement

of the trousers with respect to the shirt, and which will further be applicable with or without conventional supporting devices, such as belts, suspenders or the like.

Other objects include the provision of a simple, strong, effective, and easily operable supporting unit which will carry out the above desiderata and which is particularly designed to meet the demands of economic manufacture.

While the present invention, in its broader aspects, is applicable to various changes and modifications, and structural departures from the illustrated conception of the invention, a preferred embodiment thereof comprises a small leather or fabric casing which is centrally apertured and which supports adjacent the central aperture thereof and between the sides of the casing a bent wire key-hole loop, to which is attached a limber tab including an end button receivable through the wider portion of the aperture and movable upwardly therein to be locked within a narrow portion thereof, the arrangement being such that the lower extremities of the shirt may be secured between the loop and tab, whereby the shirt and trousers will be retained in their desired relationship, the weight of the trousers being effectively distributed over the neck and shoulder portions of the shirt so that strain is equally divided and so that wrinkling or creasing of the shirt is avoided, the support of the trousers being combined with shirt retention whereby unsightly blousing effect is avoided and the shirt is retained in smooth, unwrinkled position.

In the accompanying drawing, in which is shown some of the various possible embodiments of the several features of the invention,

Fig. 1 is a diagrammatic representation showing the device on a small scale as employed in use.

Fig. 2 is a view illustrating the construction of a waistband to removably receive the retainer of the present invention.

Fig. 3 is a plan view of the retainer.

Fig. 4 is a sectional view taken on lines 4-4 of Fig. 1.

Fig. 5 is a similar section taken on lines 5-5 of Fig. 1.

Fig. 6 is a sectional view taken on lines 6-6 of Fig. 3.

5 Fig. 7 is a view illustrating a modified form of the invention showing the retainer directly and permanently applied to an unapertured waistband.

10 Fig. 8 is a view illustrating an apertured receiving piece adapted for attachment to a conventional waistband for receiving and securing the supporting unit of the present invention, and

15 Fig. 9 is a view similar to Fig. 6 through a modified form of the retainer which utilized a supplemental protecting and strengthening backing piece.

In that form of the invention illustrated in Figs. 1 to 6, the waistband W of the 20 trousers T is provided with an elongated aperture A, the edges of which are preferably bound by suitable overcast stitchings 10.

The preferred embodiment of the invention provides, in combination with the aperture A, female snap buttons 11, which face inwardly from the waistband and which are adapted to receive protruded heads 12 of cooperating male snap buttons 13, carried by the retainer R, whereby the buttons 11 and

25 13 cooperate to secure to the inner face of the waistband the leather, canvas or equivalent small fabric holster of the retainer. The center of the retainer R is apertured as at 15 to form a keyhole opening 15. The holster

30 as shown in Fig. 6 is preferably formed of two plies of leather, canvas or equivalent strong material stitched at their edges by the stitchings 16 and similarly bound together at the edges of the aperture 15. The buttons

35 13 are preferably secured by conventional riveting to serve in the case of buttons 13, as effective joining units for the plies in addition to their peripheral stitchings.

Secured between the plies of the holster 40 14, a pinch fastener loop L is provided, the ends 17 of which extend downwardly from near the top of the holster and turn inwardly to abut for a short longitudinal distance to provide the lower closed end 18 of the

45 fastener loop. From abutting relation, they extend upwardly to form the circular portion of the loop, which portion is received between the plies of the holster. At the upper end of the circular portion, the wire of

50 the loop forms an upwardly extending reduced portion 19, which extends inwardly from the edges of the aperture 15 to provide free access for manipulations of a resilient button 20, preferably integrally formed from

55 a resilient anchoring tab 21. The inner end of the tab is apertured as at 22 to receive therethrough a securing band 23, which passes through the aperture 22 and through the lower portion of the aperture 15. Stitchings 24 of the band serve to secure it, while

its passage through the aperture 15 provides reinforcing support for the aperture and the receiving loop.

In some instances as shown in Fig. 7 the portion 19 may have an upwardly extending 70 loop 19A which extends between the plies of the holster at the upper edge of the aperture whereby the whole fastener loop is firmly secured to prevent movement of any part thereof from the plane of the holster.

In the use of the preferred form of the invention, it will be seen that the holster is 75 removably secured to the buttons 11 of the waistband, which are preferably formed during the manufacture of the trousers, the aperture A cooperating with the aperture

15 to permit easy manipulation of the tab 21 through the securing loop. As shown in 80 Fig. 4, the lower portion of the shirt S is brought down and is folded back over the loop L, the button 20 of the tab 21 is then inserted through the round portion of the loop and moved upwardly to be jammed into the 85 reduced portion 19, whereby the shirt is engaged and whereby downward stresses or strains of the trousers with respect to the shirt will be seen to more firmly lock the head or button into the portion 19, thus to firmly

90 secure the shirt and to prevent downward movement of the trousers.

In removal of the trousers, the aperture A of the waistband permits ready access of 95 a finger therethrough to engage the head and move it downwardly for disengagement from the loop. By this arrangement the trousers

100 are effectively anchored and sustained by the shirt so that downward strain of the trousers is transmitted through the shirt to be distributed over the neck and shoulder portions thereof, whereby direct, concentrated strain 105 at any portion of the shirt is avoided so that even relatively flimsy material will not receive tearing strain.

The invention accordingly, in addition to the useful functions of suspenders and belts, 110 maintains a shirt in place and prevents blousing action. Normal discomfiture, burden, and chafing from suspenders or belts is avoided.

Modifications of the invention, which form 115 a part of the inventive concept, include the provision of an assembly as shown in Fig. 7, in which the holster formed in accordance with Fig. 3 is directly stitched at its lower edges, as by the stitchings 25, to the waistband.

120 The absence of stitching at its upper edges provides for the admission of a finger to the inner side of the button in the fastening and unfastening operation. This structure also eliminates the aperture A of the waistband and the mounting of the buttons 11 thereon, and at the same time avoids the provision of buttons 13 of the holster. This arrangement therefore 125 is designed for permanent attachment to

the waistband and avoids the necessity for any modification whatsoever of the waistband.

In that form of the invention shown in Fig. 8, an apertured button receiving piece 26 is provided which may be stitched to the conventional waistband W without requiring any modification of the waistband, piece 26 serving to provide for the aperture A and the receiving buttons 11.

By reference to Fig. 9 it will be seen that a backing piece 27 may be applied to the holster after its formation as shown in Fig. 3. The piece 27 serves to protect the associated garments against contact with the exposed heads of the buttons and serves to protect and strengthen the whole assembly.

The present invention is particularly designed for use in custom made trousers, as distinct from providing an attachment to trousers as afforded by my previous patent above identified. The invention accomplishes the desired avoidance of the use of belts or suspenders, and is inherently less expensive by minimizing the amount of material employed.

It will thus be seen that there is herein described an apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters Patent, is:

1. As a new article of manufacture, a garment support embodying an apertured holster, a fastening loop enclosed by the holster and associated with the aperture thereof, and a limber tab flexibly supported from the holster, including a button receivable through the loop for engaging a shirt between the loop and button, the button lying within said aperture when received within the loop.
2. In combination with an apertured trouser waistband, a trouser support including an apertured holster arranged on the waistband with its aperture in registration with the aperture of the waistband, said support further including a securing loop partially extending within the aperture of the holster and a securing tab including a button receivable in the loop to retain a shirt between said loop and tab.
3. As a new article of manufacture, a pair

of trousers including a waistband, a garment support carried by the waistband and embodying a holster, a fastening loop enclosed by the holster and a limber tab supported from the holster including a button receivable through the loop for engaging a shirt between the button and loop. 70

4. As a new article of manufacture, a pair of trousers including a waistband, a garment support carried by the waistband and embodying an apertured holster, a fastening loop enclosed by the holster and associated with the aperture thereof, and a limber tab flexibly supported from the holster, including a button receivable through the loop for engaging a shirt between the button and loop. 75

5. As a new article of manufacture, a pair of trousers including a waistband, a garment support carried by the waistband and embodying a holster, a fastening loop associated with the holster, a limber tab flexibly supported from the holster, including a head receivable through the loop for engaging a shirt between the tab and holster, and an attaching piece for the holster, permanently secured to the waistband, said piece being apertured to provide access for manipulation of the head through the loop. 80

6. As a new article of manufacture, a pair of trousers including a waistband, a garment support carried by the waistband and permanently secured thereto at its lower edge, and embodying an apertured holster, a fastening loop enclosed by the holster and associated with the aperture thereof, and a limber tab flexibly supported from the holster, including a head receivable through the loop for engaging a shirt between the tab and holster. 95

7. As a new article of manufacture, a garment support including a holster formed of a plurality of plies of material, a pair of said plies being apertured in registration, a fastener loop extending into said aperture from between said pair of plies and including an extending end portion also extending between said plies and a flexible securing member connected with said holster and including a head receivable for fastening in said loop. 105

Signed at New York, in the county of New York and State of New York, this 30th day of June, A. D. 1930.

GEZA GREENBERG.
